S. V. REEVES

HOT WATER STOVE

Filed April 24, 1923

UNITED STATES PATENT OFFICE.

SAMUEL V. REEVES, OF HADDONFIELD, NEW JERSEY.

HOT-WATER STOVE.

Application filed April 24, 1923. Serial No. 634,240.

The object of my present invention is to devise a novel construction and arrangement of a hot water stove having a plurality of water chambers and a separate source of heat for effecting the heating of the water in said water chambers, although one or the other of such sources of heat may be dispensed with.

It further comprehends a novel construction of a hot water stove wherein a water jacketed fire pot has superimposed above it a water ring forming a continuation of such fire pot and a separate grate is employed for the water jacketed fire pot and for the water ring.

In devices of this character, it is desirable to have one of the water chambers connected with the radiators and to have one or more water chambers serve as a supply 20 of hot water for household purposes such as for the kitchen and the bath room. Where a single fire is employed, it is difficult in practice to so adjust it that heat is not wasted in the summer time when the 25 radiators are not in use.

In accordance with my present invention both fires may be in operation at the same time or a single fire employed to heat both of the water chambers. In the summer 30 time, when the radiators are not in use, the fire for only one of these water chambers is employed.

It further comprehends a novel construction of a hot water stove wherein a plurality of superimposed water chambers are employed, the inner walls of which contribute to form the fire pot with a source of heat for each water chamber, the upper grate being provided with a removable section 35 so that the proper draft can be obtained for the lower fire.

It further comprehends a novel construction and arrangement of a water jacketed fire pot, a water ring, grate supporting 40 members and grates.

Other novel features of construction and advantage will hereinafter more fully appear in the detailed description and the appended claim.

For the purpose of illustrating my invention, I have shown in the accompanying drawings embodiments thereof which are at present preferred by me, since these embodiments will be found in practice to give satisfactory and reliable results. It is, how-

ever, to be understood that the various instrumentalities of which my invention consists can be variously arranged and organized and that my invention is not limited to the precise arrangement and organization of these instrumentalities as herein shown and described.

Figure 1 represents, in sectional elevation, a hot water stove, embodying my invention.

Figure 2 represents a section on line 2—2 of Figure 1.

Figure 3 represents a section on line 3—3 of Figure 1.

Figure 4 represents a view in section 70 showing the grate sections in a different relation from that seen in Figure 3; and

Figure 5 represents, in detached position, a top plan view of a grate support.

Referring to the drawings.

1 designates the base of the stove on which is mounted a base top or ash pit ring 2 which at its upper end is provided with an inwardly extending flange 3 to receive the water jacketed fire pot 4 which is provided 80 with the water chamber 5 which is of greatest diameter intermediate its ends. The flange 3 also serves as a support for a rest supporting ring 6 having the aligned recesses 7 and 8 which are adapted to receive 85 a grate bar rest 9 the central portion of such rest being depressed. The rest is provided with the upwardly extending pin 10. The rest supporting ring 6 is provided with an annular recess 11 in its outer periphery 90 near its bottom so that it can set down into the flange 3.

12 designates a grate bar supporting ring having in its top a semicircular recess 13. 14 designates a grate cross bar from which 95 extends laterally a recessed arm 15 which seats on the pin 10 of the rest 9. The grate bar supporting ring is provided with the oppositely disposed recesses or seats 16 and with an outward extension 17 which forms 100 the equivalent of a shank and this extension is provided with an aperture 18, in order to facilitate its manipulation when it is desired to shake the grate by oscillating it in a horizontal plane. The underface of the 105 extension is recessed, as at 19. 20 designates a semicircular grate which is adapted to be received in the recess 13 and to be replaced by a flat grate 21, the grate 20 being provided with a vertically disposed front grate 110

member 22. The purpose of the upstanding grate is to divide a fire pot into two sections so that if a small fire is desired a small quantity of fuel may be used in one section without spreading all over the other section. The grate section 20 forms the rear portion of the grate, and the front portion is formed by a grate section 23 having the trunnions 24 which are received in the seats 16 of the 10 grate bar supporting ring. The grate section 23 is thus pivotally supported and it is held in its upward position by means of a pin 25 which is received in the recess 19 and passes through the aperture 26 in the 15 grate bar supporting ring 12.

The construction just described refers to the upper grate mechanism. The upper and lower rests 9 and rest supporting ring 6 are of the same construction so that they have 20 been given the same reference characters. The lower grate in Figures 1 and 2, as indicated at 27, is of the drawbar type and is provided with a draw-bar 28 and it is pivotally mounted on the pin 10 of the lower 25 rest 9. The upper rest supporting ring 6 is carried by the water jacketed fire pot 4 and contributes with such water jacketed fire pot to support a water ring 29 which is provided with a water chamber 30. A 30 top casing ring 31 is seated on the water ring 29 and is provided with a damper control exit flue 32 and with the removable lids 33. The top of the stove is adapted to be used for domestic purposes if desired.

35 The water jacketed fire pot 4 is provided with an inlet pipe 46 and an outlet pipe 47 and in a similar manner, the water ring 29 is provided with an inlet pipe 48 and a discharge pipe 49.

40 The operation of my present invention will now be readily apparent to those skilled in this art and is as follows:

45 When it is desired to provide hot water for use both in the radiators and for bath room and household purposes, the lower grate mechanism only may be employed in which case the upper grate mechanism can remain in place or it may be removed, as it has been found in practice that the draft 50 through the fire pot is not interfered with. Either the water jacketed fire pot or the water ring may be connected with the radiator system, as may be desired.

55 When it is desired to maintain a very low fire in the main or lower fire chamber, for example, enough to keep up a slow circulation of the water through the radiator, the sectional, divisional grate shown in Figures 1 to 4 inclusive may be advantageously employed. The grate section 23 may be entirely removed or the pin 25 may be drawn out, thereby permitting it to drop into the position shown in Fig. 2. The water ring section can now contain a volume of 60 fire which may vary but which in practice

is preferably about four-fifths of the capacity when the grate sections 20 and 23 are both employed. This elevated supplementary fire can be used in conjunction with the lower fire irrespective of whether the lower fire is low in volume and low burning or whether it is of normal volume and burning at maximum capacity.

If the water required from the upper water chamber is but a small quantity, the 75 upper fire may be kept a fractional size until such time as the greater quantity of hot water may be needed. The grate section 20 can then be removed and the grate sections 21 and 23 utilized so as to carry a fire equal 80 in volume to the full capacity of the water circuit of the upper water chamber. It has been found in practice that the deposit of the products of combustion from the upper contracted fire have little effect on the combustion of fuel in the lower chamber if a poker is used through the front open section of the elevated sectional grate.

85 It will be apparent from the foregoing that in accordance with my present invention, I provide a plurality of superposed and independent water chambers and a separate source of heat for each chamber, and, whenever desired, the upper source of heat may have its capacity reduced or it may be 90 eliminated. In a similar manner, the source of heat for the lower water chamber may be eliminated and only the upper source of heat employed, so that only the upper water chamber will be heated.

100 In this manner, the desired supply of hot water can be maintained at all seasons of the year and the water chambers may be heated by the same source of heat, heated by independent sources of heat, or one 105 source of heat or the other may be dispensed with in accordance with conditions and requirements met with in practice.

110 The water ring, as illustrated, forms a continuation of the fire pot formed by the inner wall of the water jacketed fire pot 4.

115 In accordance with my present invention, I employ a base or lower fire which, as illustrated, is utilized to heat a water jacketed fire pot, although it will be apparent that a fire pot which does not have a water chamber in it may be employed, if desired.

120 Above this lower fire pot, I can employ one or more water rings or water chambers, although for purpose of illustration, I have preferred to show a single water ring above the water jacketed fire pot.

125 The grate cross bar 14 forms a part of its respective grate 20 or 21. It will thus be understood that the base fire can be operated independently of or conjointly with one or more upper fires so that the hot water for one or more circuits may be effectively heated.

130 It will now be apparent that I have de-

vised a novel and useful construction of a hot water stove which embodies the features of advantage enumerated as desirable in the statement of the invention and the above description, and while I have, in the present instance, shown and described embodiments thereof which will give in practice satisfactory and reliable results, it is to be understood that these embodiments are susceptible of modification in various particulars without departing from the spirit or scope of the invention or sacrificing any of its advantages.

Having thus described my invention,

what I claim as new and desire to secure by Letters Patent, is:

A hot water stove, comprising a top casting having a lid, a water jacketed fire pot, a rest ring contributing to support it, a rest on said rest ring, a grate carried by said rest, a rest ring supported on said fire pot, a rest supported by said rest ring, a grate having a removable section supported by said rest, a water ring carried by said last named rest ring and fire pot, and a flue for the fire pot which flue extends horizontally beneath said lid.

SAMUEL V. REEVES.
